Co-pending Design U.S. Appl. No. 29/444,237, filed Jan. 28, 2013.

* cited by examiner

Primary Examiner — Elizabeth Albert(74) Attorney, Agent, or Firm — Lando & Anastasi, LLP(57) CLAIM

The ornamental design for a flower template, as shown and described.

DESCRIPTION

The sole FIGURE is a top plan view of a flower template showing my new design.

The surface inside the broken line of the outside edge of the flower template is claimed. The broken lines are included for the purpose of showing features that form no part of the claimed design.
